UNITED STATES PATENT OFFICE.

CLAUDE IVY WALLIS AND JOHN S. AMROCK, OF MOBILE, ALABAMA.

ADJUSTABLE GRATE-BAR SUPPORT.

Application filed December 4, 1926. Serial No. 152,620.

This invention aims to provide novel means whereby a grate bar, a shaker bar, or the like, may be removed readily from a furnace.

With the foregoing and other objects in view which will appear as the description proceeds, the invention resides in the combination and arrangement of parts and in the details of construction hereinafter described and claimed it being understood that changes in the precise embodiment of the invention herein disclosed, may be made within the scope of what is claimed, without departing from the spirit of the invention.

In the drawings:—

Figure 1 is a front elevation, the gears on the grate bars being omitted:

Figure 2 is a section on the line 2—2 of Figure 1;

Figure 3 is a composite view showing the bearing blocks removed from the support:

Figure 4 is a section on the line 4—4 of Figure 2.

The numeral 1 marks a furnace wall having an upper opening 2 communicating with a lower doorway 20, the doorway 20 being closed by a door 21. Over the opening 2 extends a support 3, in the form of a plate, held in place by securing elements 4, the support or plate 3 having openings 5 that communicate with the opening 2 in the wall 1. The longitudinal vertical edges of the openings 5 converge rearwardly and inwardly, as shown at 22 in Figure 4. On the said edges of the openings 5 there are ribs 6 which slant downwardly and inwardly. The upper end of the opening 5 is rounded as at 16, and at the upper end of the opening 5 there is a reinforcing flange 12.

A member 8, in the form of a block is inserted slidably into the opening 5. The longitudinal vertical edges of the block 8 converge rearwardly and inwardly, as at 24, to correspond with the slant 22 of the longitudinal vertical edges of the opening 5 in the plate 3. The block 8 is provided on its vertical longitudinal edges with ribs 9 cooperating with the ribs 6, the ribs 9 slanting downwardly and inwardly. At its upper end, the block 8 has a concaved seat 15 about which extends a reinforcing flange 11. The numeral 14 denotes a grate bar, a shaker bar, or an equivalent structure, the end of which is

mounted to rock in the seat 15 of the block 8 and in the end portion 16 of the opening 5. One of the gears by which motion is transmitted from one bar to another is shown at 17.

When the block 8 is in position as shown in Figure 2, the block will not move outwardly, that is to the left in Figure 2 because the ribs 9 and 6 slant downwardly and inwardly. The block 8 cannot move freely in a vertical direction because the ribs 6 and 9 cooperate to prevent this. The block 8 cannot slide inwardly beyond the position shown in Figure 4, owing to the cooperation between the converging edges 22—22 and 24—24.

The block 8 may be pulled forwardly and outwardly into the position shown in Figure 3 of the drawings. This sets the forward end of the grate bar or shaker bar free, and when the door 21 is opened, the forward end of the grate bar or shaker bar may be dropped downwardly, the bar being removed without difficulty. By reverse process, a new bar can be mounted quickly in place.

What is claimed is:—

In a device of the class described, a plate-like support having an upwardly extended opening in its lower edge, and a bearing member in the opening, the upper end of the bearing member being spaced from the upper end of the opening to afford a place of journaling for a grate bar; the vertical longitudinal edges of the bearing member, and the corresponding members of the support, being provided with interengaged ribs which cooperate to hold the bearing member against dropping downwardly out of the opening, the bearing member tapering in width from front to back, and the longitudinal edges of the opening being correspondingly inclined from front to back, thereby to prevent the bearing member from sliding through the opening in a substantially horizontal direction, and the ribs slanting downwardly and inwardly to cause the bearing member to move rearwardly to a firm seat in the opening of the support.

In testimony that we claim the foregoing as our own, we have hereto affixed our signatures.

CLAUDE IVY WALLIS:
JOHN S. AMROCK.
